TABLE ORNAMENT

Herbert U. Dernehl, Milwaukee, Wis.

Application August 13, 1934, Serial No. 739,631

4 Claims. (Cl. 41—10)

This invention relates to improvements in table ornaments and refers more particularly to imitation floral pieces.

It is an object of this invention to provide an ornament of the character described which is adapted to be sold in knocked down form.

Another object of this invention is to provide an ornament of this type which is of simple construction and capable of being manufactured in

10 large quantities at very low cost.

Another object of this invention is to provide a table ornament made entirely of stamped sheet metal so constructed as to enable its being sold in knocked down flat form to be set up by the 15 purchaser to represent a floral display.

With the above and other objects in view which will appear as the description proceeds, this invention resides in the novel construction, combination and arrangement of parts substantially 20 as hereinafter described and more particularly defined by the appended claims, it being understood that such changes in the precise embodiment of the hereindisclosed invention may be made as come within the scope of the claims.

25 The accompanying drawing illustrates one complete example of the physical embodiment of the invention constructed according to the best mode so far devised for the practical application of the principles thereof, and in which:

30 Figure 1 is a perspective view of the ornament set up and ready for use;

Figure 2 is a plan view of one of the two parts of the device in its flat form as sold; and

35 Figure 3 is a plan view of the base of the ornament.

Referring now more particularly to the accompanying drawing, the numeral 5 designates the base of the ornament which in the present instance is in the form of a disc of sheet metal 40 having diametrically opposite ears 6 from which attaching tangs 7 project.

The ears 6 are adapted to be folded up on a line substantially forming a cord connecting the opposite inner corners of the ears to mount an 45 arch-like band 8 which is attached to the ears by engaging the tangs 7 in suitable openings 9.

The band 8 is formed by a central solid portion of a sheet of thin flexible metal 10 whose opposite end portions are slit as at 11 to divide 50 the same into a multiplicity of narrow ribbons or streamers 12 which, when the ornament is set up, extend haphazardly from the arch band 8 as illustrated in Figure 1 and have imitation flowers 12' fixed to their outer ends.

55 The feature of the invention resides in the fact

that the two major parts from which the ornament is made, namely the base and sheet 10 which is slit to provide the streamers and the arched band 8, may be prepared ready for use and sold in a flat state as shown in Figures 2 and 3. In this condition, these two parts, with or without a supply of paper flowers, may be put up for sale as an article of commerce, and in view of the exceptionally low cost of the article, it finds an excellent market in five and ten cent stores.

10 To assemble the ornament, it is only necessary to bend up the ears 6 on the base and attach the opposite ends of the band 8 thereto by engaging the tangs 7 in the holes 9 and bending them down as illustrated in Figure 1.

15 In view of the fact that the width of the sheet 10 from which the band and the streamers are formed, is greater than the diameter of the base, it follows that when mounted on the base, the band assumes an arched shape to provide an attractive support for the streamers.

20 The appearance of the ornament may be enhanced by twisting the streamers or stems if desired.

25 What I claim as my invention is:

1. A table ornament of the character described comprising, a base, a sheet metal band attached at its ends to the base and arched across the top of the base, and a plurality of ribbon-like streamers extending in all directions from the opposite side edges of said sheet metal band, said band and streamers being integrally connected.

2. A table ornament of the character described, comprising a base, a sheet metal band attached at its ends to the base and arched across the top of the base, a plurality of ribbon-like streamers extending in all directions from the opposite side edges of said sheet metal band, said band and streamers being integrally connected, and imitation flowers attached to the extremities 40 of said ribbon-like streamers.

3. As an article of commerce, an ornament in knocked down form to be set up by the purchaser, comprising, a flat sheet of thin flexible metal substantially rectangular in shape and slit from its opposite ends toward the center thereof but short of the center of said sheet, whereby said sheet has an unslit central portion providing a band extending transversely across the sheet and a multiplicity of parallel ribbon-like strips extending from the opposite side edges of said band to the ends of the sheet, and a base having means to which the opposite ends of said band are attachable, said attaching means of the base being spaced apart a distance less than the length of 50 55

said band, whereby attachment of the band thereto causes the band to assume an arched shape over the base.

4. The hereindisclosed method of making a table ornament of the character described, which consists in slitting a substantially rectangular piece of sheet metal from opposite ends toward the center to divide said piece of sheet metal into a plurality of parallel ribbon-like strips at op-

posite sides of a central unslit portion, bending the sheet transversely so that its unslit portion provides a band substantially in the shape of an arch, attaching the ends of said arched band to a base, bending the ribbon-like strips up from the opposite side edges of the arched band, and attaching imitation flowers to the extremities of said ribbon-like strips. 5

HERBERT U. DERNEHL.
